UNITED STATES PATENT OFFICE.

EARL D. SWISHER, OF DES MOINES, IOWA.

BARKING TOY.

Application filed June 13, 1927. Serial No. 198,429.

The object of my invention is to provide a barking toy of simple, durable, and comparatively inexpensive construction.

A further object is to provide a toy of this character in which a sound can be produced simulating the barking of a dog.

Still a further object is to provide such a device in the form of a casing having a diaphragm therein with a bar slidably mounted through an opening in the diaphragm and constrained to at all times contact with one side of the opening whereby movement of the bar relative to the casing will produce a sound.

Still a further object is to provide a means for moving the bar with relation to the diaphragm and in my drawing I have illustrated one embodiment of a device for so moving the bar.

With these and other objects in view, my invention consists in the construction, arrangement and combination of the various elements of my invention whereby the objects contemplated are attained, as hereinabove set forth, pointed out in my claims and illustrated in the accompanying drawing, in which:

Figure 1 is a perspective view of my barking toy illustrating its normal position in full lines and another position in dotted lines as when it is operated to cause a barking sound.

Figure 2 is an enlarged sectional view through the sound producing portion of the device.

Figure 3 is a similar view showing the parts in another position; and

Figure 4 is a detail sectional view taken on the line 4-4 of Figure 2.

On the accompanying drawing I have used the reference numeral 10 to indicate a ring adapted to be positioned over a finger of a person operating the toy to produce a barking sound. A link 12 extends from the ring 10 and is pivotally or swivelly secured at 14 to a wiener 16. In the illustration of my device I have simulated a string of wieners as one embodiment of my invention. The wiener 16 may be formed of any suitable material and may be ornamented with a dog collar 18 if so desired.

Suspended from the lower end of the wiener 16 is a flexible cable 20 pivotally secured to a sounding bar 22. The sounding bar 22 extends into a second wiener 24. Sus-

pended from the wiener 24 by a flexible cable 26 is a third wiener 28, preferably weighted, the purpose of which will hereinafter be described.

The wiener 24 comprises a casing, a portion 30 of which is metallic. Substantially midway of the wiener 24, the portion 30 of the casing terminates in a diaphragm 32. An opening 34 is formed in the diaphragm 32.

Secured to the upper end of the portion 30 of the wiener 24 is a head 36 formed of a suitable non-metallic material. The bar 22 extends slidably through an opening 38 in the head 36 and into the wiener 24. The bar 22 terminates below the diaphragm 32 after having passed through the opening 34. It may here be mentioned that the opening 34 is larger than the bar 22 to allow its free sliding movement therethrough.

A spring 40 has one end secured to the portion 30 of the casing and has its other end secured to a lug 42 on the bar 22. A suitable stop 44 may be provided on the bar 22 for preventing too much upward movement of the bar 22 relative to the diaphragm 32 whereby to prevent the bar moving completely up through the opening 34 in the diaphragm. Secured to the portion 30 of the wiener 24 is a second casing portion 46 preferably non-metallic in composition. The diaphragm 32, I find, works best when made of a thin tin and the bar 22 should be fairly heavy and works best when made of iron although I do not wish to limit myself to these materials.

Practical operation.

In operating my barking toy to produce a barking sound the device is held suspended from the operator's hand by holding the ring 10. The device is then moved downward whereby all three wieners 16, 24, and 28 move downwardly and the downward motion of the operator's hand is then stopped whereby the movement of the wiener 16 and the sounding bar 22 is also stopped. The momentum acquired by the weighted wiener 28 will carry it on downwardly carrying with it the wiener 24 which has the diaphragm 32 formed therein. This causes the diaphragm 32 to move with relation to the bar 22 so that the bar being held against one side of the opening 34 and the diaphragm will scrape thereagainst for produc-

ing a sound similar to the barking of a dog. The movement of the diaphragm 32 with relation to the bar 22 continues against the action of the spring 40 as illustrated in Figure 3 until the tension of the spring overcomes the gradually decreasing momentum of the wiener 28.

Another downward movement of the ring 10 will slide the bar 22 in a downward direction causing it to again scrape against the edge of the opening 34 in the diaphragm for producing a further sound. The operation is repeated by slowly moving the ring 10 up and down, the speed of which movement can be regulated to suit the desires of the operator so that the dog will bark fast or slowly.

From the description of my invention it will be obvious that the sound producing mechanism is entirely contained within the wiener 24 and consists of the casing portions 30 and 46, the diaphragm 32, the bar 22, the head 36 and the spring 40. It will therefore be obvious that the sound producing unit can be made into toys of various other shapes and it is only necessary in order to produce a sound like the barking of a dog to provide for movement of the bar 22 relative to the diaphragm 32.

30 The diaphragm 32 may be arranged at an oblique angle relative to the bar 22 so that a slightly different sound is produced when the bar slides through the opening 34 in one direction than when the bar slides in 35 an opposite direction.

The head 36 may be made thicker if desired so that the bar 22 will be completely concealed within it. In this event, the cable 20 would extend down into the head 36 to 40 connect to the bar 22.

Some changes may be made in the construction and arrangement of the various parts of my invention, without departing from the real spirit and purpose of my invention, and it is my intention to cover by 45 my claims, any modified forms of structure or use of mechanical equivalents, which may be reasonably included within their scope.

I claim as my invention:

50 1. A device of the class described com-

prising a metallic tube having a diaphragm at one end thereof, an opening in said diaphragm, a bar slidably mounted through said opening, non-metallic guide means in the other end of said casing for said bar, a 55 spring connecting said bar to said casing for maintaining the bar in engagement with one side of the opening in said diaphragm and a non-metallic sounding chamber forming a 60 continuation of said metallic casing.

2. A device of the class described comprising a metallic casing, a diaphragm at one end thereof, a non-metallic extension secured to said metallic casing, an opening in said diaphragm, a bar associated with said opening for producing a sound upon sliding movement of the bar and means for causing such sliding movement, said means comprising a weight suspended from said non-metallic extension whereby movement of said bar 70 up and down will cause movement of said diaphragm relative to said bar.

3. A device of the class described comprising a casing, a diaphragm therein, an opening in said diaphragm, a bar associated with 75 said opening, resilient means constraining said bar to contact with one edge of said opening for producing a sound upon sliding movement of the bar and means for causing such sliding movement, said means comprising a weight suspended from said casing whereby moving said bar up and down will cause said weight to move said diaphragm relative thereto.

4. A device of the class described comprising a casing, a diaphragm therein, an opening in said diaphragm, a bar slidably mounted through said opening, guide means and a spring connecting said bar to said casing for maintaining the bar in engagement with one side of the opening in said diaphragm for producing a sound upon sliding movement of the bar and means for causing such sliding movement, said means comprising a weight suspended from said casing whereby moving said bar up and down will cause said weight to move said diaphragm relative thereto.

EARL D. SWISHER.
